UNITED STATES PATENT OFFICE.

ARTHUR LEON ARMENTROUT, OF WHITTIER, CALIFORNIA, ASSIGNOR OF ONE-HALF
TO THE GUIBERSON CORPORATION, OF DALLAS, TEXAS, A CORPORATION OF DELA-
WARE.

PISTON.

Application filed May 7, 1923. Serial No. 637,312.

To all whom it may concern:

Be it known that I, ARTHUR LEON ARMENTROUT, a citizen of the United States, and a resident of Whittier, county of Los Angeles, 5 and State of California, have invented a new and useful Piston, of which the following is a specification:

The present invention relates to improvements in pistons reciprocating in cylinders 10 and its particular object is to provide means in connection with a piston that will prevent a pressure medium actuating the piston or actuated by the piston from leaking past the piston. My improvement has particular reference to and will be described in 15 connection with a pump and more particularly a force or pressure pump although not confined to that particular device. It is proposed in the present invention to utilize 20 the pressure of the medium acted on for effecting a pressure-tight engagement between a circumferential ring or sleeve on the piston and the wall of the cylinder. More particularly it is proposed to allow the pressure 25 medium acted on by the piston to pass underneath the ring so as to force the same away from its seat into engagement with the cylinder wall, and to furthermore provide a pumping mechanism within the main piston 30 adapted to be acted on by the pressure medium on the working stroke of the piston, and to force a charge of the pressure medium between the piston and the ring. It is further proposed to provide check valves 35 within the passages allowing the pressure medium to enter underneath the piston ring so as to prevent the pressure medium from escaping on the inactive stroke of the main piston. Further objects and advantages 40 will appear as the specification proceeds.

The preferred form of my invention is illustrated in the accompanying drawing in which Figure 1 shows a longitudinal section through a pump using my piston; Figure 2 a longitudinal section through the piston itself taken along line 2-2 of Figure 3; Figure 3 an end view of the piston as viewed from the right hand side with certain portions shown broken away and Figure 4 a 50 sectional view similar to that of Figure 2 with the main working unit shown in side elevation. While I have shown only the preferred form of my invention, it should be understood that various changes or modifications 55 may be made within the scope of the

claims hereto attached without departing from the spirit of the invention.

In Figure 1 is shown the cylinder (1) of any suitable type of continuous delivery force pump with a piston (2) on the pump 60 rod (3) reciprocating therein. On a stroke to the left a fluid medium such as water is drawn into the cylinder through a port (4) and delivered through the port (6), while when the piston moves to the right the liquid medium is forced outwardly through the port (4) and sucked into the cylinder through the port (6). A valve mechanism not shown in the drawing allows of this operation. The principal feature of the 70 present invention is the construction of the piston (2). The latter comprises a cylinder (7) confined between two discs (8) and (9), which latter are forced upon the cylinder in any suitable manner, as for instance by 75 means of the bolts (11) engaging their threaded ends, with the heads of the bolts and the nuts disposed on opposite sides of the two discs. The cylinder (7) is surrounded by a plurality of rings (13), preferably three in number, which are made of yielding material such as rubber for instance, and disposed in adjacent relation in such a manner as to slightly project circumferentially beyond the discs (8) and (9). 85

The piston rod (3) is reduced in diameter to form a shoulder (14) and is tapered beginning from said shoulder as shown at (15) to engage a bushing (16) disposed between the two discs (8) and (9). It is held in 90 place by means of the nut (17) which latter is locked against rotation by a second nut (18). A heavy ring (19) fills the space between the cylinder (7) and the bushing (16) and is provided with a plurality of recesses 95 (21) in either end adapted to have plugs (22) inserted therein by means of a threaded engagement (23). Preferably four of these plugs are provided in symmetrical arrangement at either end, each two plugs in 100 opposite ends being axially alined. The plugs are recessed again as shown at (24) and receive the plungers (26) which are limited in their outward motion by means of externally threaded nuts (27) threadedly engaging the plugs (22). The springs (28), bearing at one end on shoulders (29) formed in the plugs and at the other end on shoulders (31) formed on the pistons, tend to 105 force the plungers (26) upon the nuts (27). 110

The inner ends of the plungers, which are reduced to form the shoulders (31), are adapted to slide into a reduced portion of the recess in the plugs (22).

5 The reduced recess in the inner end of each plug connects with a perforation (32) of the same diameter, which latter perforation extends through that portion of the ring (19) not occupied by the two opposing 10 plugs and the center of said recess communicates with a radial passage (33) leading into a longitudinal slot (34) in the cylinder (7), which latter slot connects with a plurality of circumferential grooves (36), each 15 groove being disposed centrally under one of the rings (13). Corresponding central perforations in the plugs (22), the nut (27) and the discs (8) and (9) open a continuous passage from the exterior into the recess 20 (32) connecting through the ports (33) with longitudinal slots (34) and the circumferential grooves (36). The longitudinal part of each passage is controlled by means of two 25 spring actuated check valves (37) and (38), which allow the liquid medium to enter into the piston but prevent the same from flowing 30 backward. The radial port (33) which communicates with two of the longitudinal passages is also controlled by a check valve (39).

The operation of this piston may be described as follows: When the piston as viewed in Figure 1 moves to the right so as to force a charge through the port (4) and 35 to draw in a charge through the port (6), the left hand plunger (26) is forced upon its seat by the spring (28) and liquid enters through the check valve (37) into the interior of the plunger, which liquid, on the 40 next left hand stroke, is forced through the check valves (38) into the chamber formed by the recess (32), the port (33), the slots (34) and the grooves (36). On the same stroke the right hand end of the main piston (2) forces the liquid outwardly and the liquid bearing on the plunger (26) on the right hand side forces the same inwardly so as to force its charge collected during 45 the previous stroke through the check valve (38) into the chamber previously described, with the result that the additional liquid forced into the chamber lifts the central peripheral portions of the three flexible rings (13) off their seats and into close contact 50 with the wall of the cylinder. On a left hand stroke, the left end of the piston becomes the pressure side, and the left hand plunger (26) delivers its charge to the chamber, while the right hand plunger is 55 seated by its operation (28) and draws in a new charge, so that the same result is obtained whether the piston moves to the right or to the left, the check valves preventing the liquid from flowing backwardly.

60 65 Particular attention is called to the fact

that the actual force brought to bear on the liquid in the chamber depends on the construction of the internal plungers. If for instance, the outer face of the plungers (26) expose a surface to the liquid medium within 70 the cylinder substantially coextensive with the inner face bearing on the liquid within the chamber, the pressure exerted will correspond to the pressure delivered. If for instance, the pressure in the cylinder is one 75 thousand pounds per unit area, the same pressure will be exerted on the liquid in the chamber. If the exposed portion of the outer face is less than the inner face of the plunger (26) the pressure on the liquid 80 in the chamber will be decreased accordingly, while when the exposed part of the outer face is larger than the inner face of the piston, the pressure will be increased, so that the dimensions for the piston may be 85 selected to suit conditions. This is particularly desirable where the pressure within the cylinder is so high that a full application of the pressure would prove destructive to the piston. 90

I claim:

1. In a pressure pump having a cylinder and a piston reciprocating therein, an expandable wall engaging element on the piston and a pumping mechanism within the piston actuated by the pump pressure for forcing the said element against the wall on the working stroke of the piston. 95

2. In a pressure pump having a cylinder and a piston reciprocating therein, an expandable wall engaging element on the piston and a plunger adapted to reciprocate in the piston parallel to its axis made to receive a charge on the inactive stroke of the piston and to deliver the same to the expandable element for forcing the latter against the wall on the working stroke. 100

3. In a reciprocating piston of the character described having pressure strokes alternating with suction strokes, an expandable ring element surrounding the piston and a pump mechanism with the piston adapted to receive a charge of a pressure medium on the suction stroke and to deliver the same to the ring element on the pressure stroke for expanding the latter. 110

4. In a reciprocating piston of the character described having pressure strokes alternating with suction strokes, an expandable ring element surrounding the piston and a pump mechanism with the piston adapted to receive a charge of a pressure medium on the suction stroke and to deliver the same to the ring element on the pressure stroke for expanding the latter, comprising a longitudinal passage in the piston communicating with the inner face of the ring element and a valved plunger slidably within said passage. 120

5. In a reciprocating piston of the char- 130

- acter described having pressure strokes alternating with suction strokes, an expansible ring element surrounding the piston and a pump mechanism within the piston adapted 5 to receive a charge of a pressure medium on the suction stroke and to deliver the same to the ring element on the pressure stroke for expanding the latter, comprising a longitudinal passage in the piston communicating 10 with the inner face of the ring, a valved plunger slidable within said passage and spring means for seating the plunger on the suction stroke.
6. In a reciprocating piston of the character described having pressure strokes alternating with suction strokes, an expansible ring element surrounding the piston and a pump mechanism with the piston adapted to receive a charge of a pressure medium on 15 the suction stroke and to deliver the same to the ring element on the pressure stroke for expanding the latter, comprising a longitudinal passage in the piston communicating with the inner face of the ring, a valved plunger slidable within said passage and a second valve in the passage for preventing back flow on the suction stroke.
7. In a double-acting reciprocating piston of the character described having pressure 20 strokes alternating with suction strokes at either end, an expansible ring element surrounding the piston and axially alined pump mechanisms in either end of the piston, each adapted to receive a charge of a pressure medium on the suction stroke and to deliver the same on the pressure stroke to the ring element for expanding the latter.
8. In a double-acting reciprocating piston of the character described having pressure 25 strokes alternating with suction strokes at either end, an expansible ring element surrounding the piston and axially alined pump mechanisms in either end of the piston, each adapted to receive a charge of a pressure medium on the suction stroke and to deliver 30 the same on the pressure stroke to the ring element for expanding the latter, the pump mechanisms comprising alined longitudinal passages in the piston having a common communication with the inner face of the ring, valved plungers slidable within the same and a second valve in each passage for preventing back flow on the suction strokes.
9. In a double-acting reciprocating piston of the character described having pressure 35 strokes alternating with suction strokes at either end, an expansible ring element surrounding the piston and axially alined pump mechanisms in either end of the piston, each adapted to receive a charge of a pressure medium on the suction stroke and to deliver 40 the same on the pressure stroke to the ring element for expanding the latter, the pump mechanisms comprising alined longitudinal passages in the piston having a common communication with the inner face of the ring, valved plungers slidable within the same and a second valve in each passage for preventing back flow on the suction strokes.
10. In a double-acting reciprocating piston of the character described having pressure 45 strokes alternating with suction strokes at either end, an expansible ring element surrounding the piston and axially alined pump mechanisms in either end of the piston, each adapted to receive a charge of a pressure medium on the suction stroke and to deliver 50 the same on the pressure stroke to the ring element for expanding the latter, the pump mechanisms comprising alined longitudinal passages in the piston having a common communication with the inner face of the ring, valved plungers slidable within the same and a second valve in each passage for preventing back flow on the suction strokes.

ARTHUR LEON ARMENTROUT.
